Primary Examiner — Prabhakar Deshmukh(74) *Attorney, Agent, or Firm* — Bose Corporation(57) **CLAIM**

The ornamental design for a control console, substantially as shown and described.

DESCRIPTION

FIG. 1 is a perspective view of a control console as seen from the front, top and side;

FIG. 2 is a front view thereof;

FIG. 3 is a rear view thereof;

FIG. 4 is a top view thereof;

FIG. 5 is a bottom view thereof;

FIG. 6 is an opposite side view thereof; and,

FIG. 7 is a side view thereof.

The dotted line portions of the drawings represent environmental structure only and form no part of the claimed design.
